WILLIAM NEES, OF DREXEL HILL, PENNSYLVANIA.

DIE AND METHOD OF FORMING ARTICLES FROM SHEET METAL.

1,286,723.

Specification of Letters Patent.

Patented Dec. 3, 1918.

Application filed December 19, 1917. Serial No. 207,849.

To all whom it may concern:

Be it known that I, WILLIAM NEES, a citizen of the United States, and a resident of Drexel Hill, county of Delaware, State of Pennsylvania, have invented certain new and useful Improvements in Dies and Methods of Forming Articles from Sheet Metal, of which the following is a specification.

My invention relates to dies for forming and pressing sheet metal plates into different shapes.

Although the principle of my invention may be employed in the construction of apparatus for pressing and shaping various kinds and characters of devices from sheet metal, it is especially adapted for use in the manufacture of throat sheets for boilers of the locomotive type.

One of the objects of my invention is to provide an improved construction which may be employed for forming flanges at different parts or positions upon a sheet metal plate after a single heating of the said plate.

It is also an object of my invention to provide dies so arranged and related to each other and so coöperating as to produce with economy and rapidity devices of sheet metal which may be described as relatively complex and which, as far as I am aware, have heretofore been manufactured by hand.

A further object of my invention is to provide a construction comprising dies which co-act with each other to form flanges upon certain portions of a sheet metal plate, and certain of which after the formation of such flanges operate to hold the said sheet while another one of which, a forming die, acts upon another portion of said plate and co-acts with one of the other of said dies to form flanges upon or rather to shape other portions of the said plate to thereby form the said plate into the shape desired, depending upon the article being manufactured.

In the drawings I have shown my invention as embodied in an apparatus designed and adapted for the manufacture of the throat sheets of boilers of the locomotive type, as above stated. In the manufacture of such throat sheets the dies coöperate to produce first the flanges at the opposite edges of the sheet, which flanges, when the throat piece is in use, usually occupy a vertical position. Certain of the said dies, after the formation of the side flanges, operate to hold the sheet, while the belt or waist flange,

which hugs the boiler shell, is being completed by the action of the forming die to which reference has been made previously.

A further object of my invention is to provide an improved process of forming an article of the character described from sheet metal, whereby the said article may be formed economically and rapidly with one heating.

In order that my invention may be readily understood and its practical commercial advantages fully appreciated, reference may be had to the accompanying drawings in which I have illustrated one form of apparatus embodying my invention and by the employment of which the improved process invented by me may be practised.

It should be understood, however, that changes in the shape and details of construction of the dies entering into the construction of the apparatus embodying my invention and that changes in the manner in which the parts of the apparatus coöperate with each other may be made within the scope of the claims without departing from my invention.

In the drawings:—

Figure 1 is a top plan view of the dies in assembled relation constituting my invention;

Fig. 2 is a top plan view of the bottom die;

Fig. 3 is a vertical sectional view taken on the line 3—3 of Fig. 1;

Fig. 4 is a view in rear elevation of the dies in assembled relation;

Fig. 5 is a view in front elevation of the dies in assembled relation;

Fig. 6 is a transverse sectional view taken on the line 6—6 of Fig. 1; and

Fig. 7 is a view showing the product manufactured by the use of the apparatus shown in the previous figures.

Referring to the drawings, 1 designates the lower die of an apparatus embodying my invention, said die having raised sides 2, the inner surfaces of which are curved, as shown at 3, so as to merge into the bottom surface 4 of the die. The said die is provided with an opening 5 of the shape of the segment of a cylinder and the front upper edge of which is curvilinear as shown at 6. The inner surfaces of the raised sides 2 of the die widen out toward the rear ends of said die and merge into opposite side portions 7 of the

opening 5. The rear ends of the sides are connected by the cross-member 10, the opposite ends of which are provided with raised portions 11 constituting continuations of 5 the sides 7 of the opening 5.

The opposite sides 12 of the top die 14 are shaped so as to enter between the raised sides 2 and the portions 11 of the lower die with such clearance as may be necessary depending upon the thickness of sheet metal stock being operated upon. The top die 14 is provided with an opening 15 corresponding in size and shape and being in alignment with the opening 5 of the bottom or 10 lower die, the lower side portions of the top die 14, at the opposite sides of the opening 15 disappearing or vanishing as indicated in Figs. 1 and 3, more particularly the latter, at 15^a. The said top die is also 15 provided with a lateral projecting and overhanging portion 16 which serves to strengthen the same, more particularly the portions thereof at and adjacent to the points of connection between the cross-member 17 and the opposite side of said die, thereby making the die self-contained. The 20 said overhanging portions serve as supports and connections for the said cross-member 17.

30 It will be observed that the tops of the sides 2 and of the portions 11 of the bottom die 1 are in the same plane and that the surface 4 and the top surface of the cross-member 10 intermediate the opposite raised 35 end portions 11 thereof are also in substantially the same plane.

The plate to be operated upon is shown in dash and dot lines 20 in Fig. 1, the said plate being indicated between the opposing 40 faces of the dies and before the same has been acted upon thereby.

These dash and dot lines 20 indicate the outline or edge of the plate.

An intermediate portion of the plate is cut 45 out or removed, the outline or portion of the said plate so removed being indicated by the dash and dot lines 21.

The portion, as indicated by the dash and dot lines 21 having been cut from the plate 50 and the said plate having been heated to the required temperature, it is placed in position upon the top side of the bottom die 1, the said plate resting upon the tops of the raised sides 2 and of the raised portions 11 at the opposite ends of the connecting member 10.

Thereafter the bottom die is moved upwardly by any suitable power actuated means so as to cause the raised sides 2 and 60 the raised portions 11 of the said bottom die to pass up on opposite sides of the lower part of the top die, as best shown in Figs. 4, 5 and 6.

The bottom die 1 in moving into the position with respect to the top die 14 and

the forming die 30, as shown in Fig. 3 of the drawing, causes the formation of the flanges 25 upon the opposite edges of the sheet metal plate, the outline of which is shown in Fig. 1 of the drawing. In moving to such position, it is the upper portions 70 of the opposite sides 7 of the opening 5 of the bottom die 1 which coöperate with the opposite side portions of the die 30 corresponding in position to the portions 7 which 75 form the portions of the flanges 25, which correspond in positions to the positions of the coöoperating parts of the forming die 30 and the bottom die 1.

The coöperation of the dies up to this 80 point of the operation of the apparatus does not affect the semi-circular portion 26 of the said plate nor the straight tongue portion 27 thereof. After the dies have operated upon the sheet metal plate to form the 85 flanges 25 and while the bottom and top dies still occupy the positions shown in Figs. 3, 4, 5 and 6, in which positions they clamp and hold firmly the said plate, the forming die 30 which is of the same shape of the 90 openings 5 and 15 through the bottom and top dies is caused to move downwardly from a position such as that shown in Fig. 3 to the position indicated in Fig. 6, so as to 95 bend the portions 26 and 27 downwardly to form flanges 26 and 27, as shown in Fig. 3, the flange 26 constituting the belt or waist flange of the device. The outer end portions of the flange 26, as shown in Fig. 7, are in the same planes as the outer end portions 100 of the flanges 25. In Fig. 3 the forming die 30 is shown in withdrawn position to which it has been moved after having been operated to turn the portions 26 and 27 downwardly into the positions shown in Fig. 3. 105

After the parts 26 and 27 have thus been turned into the position shown in Fig. 3 to form flanges, as thus described, the opposite leg portions of the plate are cut along a line at 33 so as to remove the portion including the tie-plate part 34 of said plate, so that the final product as made by the particular construction of dies 1 and 14 and forming die 30 illustrated and described and as shown in Fig. 7 of the drawings is produced.

The forming die 30 is connected at its upper side with a portion 35 having connection with means (not shown) for causing it to reciprocate and thereby cause operative movements thereof to bend down the parts 26 and 27 to form flanges as shown in Fig. 3.

The purpose of the tongue 27 is to provide counteracting pressure against the 125 plunger 30 in opposition to the pressure exerted against said plunger by the semi-circular portion 26. Were it not for the presence of the tongue 27 the plunger would tend to cant or tilt by reason of the fact 130

that the resistance encountered thereby in its movement downwardly would be only upon the one side.

It will be observed that I have provided 5 a single unitary construction of apparatus for forming the side flanges 25 and the belt flange 26, the latter merging at its opposite ends into the upper ends of the side flanges 25. The said belt flange and the upper ends 10 of the side flanges hug a greater or less portion of the outer cylindrical surface of a shell and are riveted thereto in known manner.

It will also be observed that the formation 15 of the belt flange 26 immediately succeeds the formation of the side flanges 25 and that while the first is being formed the dies by means of which the side flanges were formed are held in what may be termed 20 clamping relation to each other to hold the plate firmly in position, while the forming die 30 operates to form the belt or waist flange 26.

It will be observed also that the construction 25 of apparatus embodying my invention is such that I am enabled to arrange the co-operating parts thereof in such relation to each other as to cause the side flanges of the device shown in Fig. 7 to merge at their 30 upper ends into the opposite end portions of the belt flange 26, the two flanges at their upper end portions occupying the same plane.

The sheet metal blank formed as above 35 described may be regarded as comprising two parts, one of which is employed to form the final product and the other to facilitate the operation of forming the said product and which is removed, as described, after 40 the process of shaping the said blank by the action of the dies has been completed.

I claim:—

1. In combination, lower and upper dies, 45 said dies having openings therethrough, one side of each of the said openings being curvilinear and the sides opposing the curvilinear sides of said openings being substantially straight and one of the said dies being provided with raised or projecting side portions 50 which diverge from each other toward their rear ends and the other one of said dies being adapted to enter the space between the said raised or projecting side portions to form side flanges upon a plate and a forming die adapted to move back and forth 55 through the said openings, said forming die operating to form a curvilinear flange upon the said plate, the opposite end portions of said flange merging into and being in substantially the same plane as the adjacent end 60 portions of the said side flanges.

2. Apparatus of the character described 65 adapted to operate upon a sheet metal plate having an opening therethrough, the said apparatus comprising lower and upper dies,

the lower dies having raised or projecting side portions which diverge from each other toward their rear ends and the said die having an opening therethrough, said opening being in the form of the segment of a cylinder and the upper die being adapted to enter the space between the said raised or projecting side portions and said upper die also being provided with an opening therethrough of the same shape as and in alignment with the opening in the lower die and a forming die of the shape of the segment of a cylinder adapted to move back and forth through the said openings, the said dies first operating to form side flanges upon 70 the said plate extending in one direction respecting the plane of said plate and the said punch operating to form flanges upon said plate extending in opposite directions with respect to the plane of said plate and one of 75 said flanges being curvilinear and being situated intermediate the first named flanges and merging at its opposite end portions into the adjacent end portions of the said first named flanges.

3. In combination, lower and upper dies having openings therethrough, the lower portions of the said upper die at the opposite sides of said opening terminating at points in front of the rear ends of the upper portions of the said opposite sides and said upper die having laterally projecting and overhanging portions, and a forming die operating in said openings.

4. In combination, two dies adapted to 100 co-act to form flanges at the opposite edges of a plate, said dies having openings extending therethrough, the flange forming part of one of said dies at the opposite sides of said opening being interrupted, and a forming die operating through said openings, the said forming die co-acting with one of the first mentioned dies during the formation of the said flanges to assist in the formation thereof and the said forming die subsequently moving through the said openings to press other portions of said plate into the shape desired.

5. In combination, male and female die members adapted to co-act to form flanges at the opposite edges of a plate, said die members having openings extending therethrough, said openings being in alignment with each other, and a forming die co-operating with the said female die in the formation of the said flanges, the said forming die, after the formation of said flanges, moving through the opening in the said female die to shape other portions of said plate, substantially as described.

6. In combination, lower and upper dies, the former being provided with side portions between which the upper die is adapted to be received and the said dies having openings extending therethrough, the op- 130

posite sides of said dies at the rear of said openings being connected by cross members, the lower portions of the upper die on opposite sides of the opening therethrough terminating in front of the cross member of said die, the said upper die being provided with an overhanging portion which is connected with and supports the cross member of said die and a forming die 10 operating in and through said openings, substantially as described.

7. In combination, lower and upper dies adapted to co-act with each other to form flanges at the opposite edges of a plate, said dies each having openings extending therethrough, one side of each of said openings being curvilinear, the lower portion of the curved side of one of the said dies terminating at its opposite ends distances in advance of the termination of the curved side of the opening through the other die, a forming die situated in and operating through the said openings, said die co-acting with one of the said dies in the formation of the said flanges and thereafter moving through the said openings to form another flange upon said plate intermediate the first named flanges.

8. In combination, lower and upper dies, 30 the lower die being provided with opposite side portions between which the upper die is adapted to be received, the said dies co-acting to form flanges at the opposite edges of a plate and the said dies having openings 35 extending therethrough, said openings being semi-cylindrical in shape in cross section, the opposite sides of the said dies beyond said openings being connected by cross members which respectively constitute portions 40 of the lower and upper dies, the lower portions of the upper die at the opposite sides of the opening therethrough terminating a distance from the cross member connecting the said opposite sides, and a forming die adapted to operate through the 45 said openings and co-act with the curvilinear side of the opening through the lower

die to form a flange upon said plate intermediate the flanges at the opposite edges thereof and which extends in a direction opposite that in which the said edge flanges extend. 50

9. In combination, male and female die members adapted to co-act to form flanges at the opposite edges of a plate and the said dies having openings extending therethrough, said openings having the shape transversely of the segments of a cylinder, the opposite sides of the said dies beyond said openings being connected by cross 60 members which respectively constitute portions of the said dies, the inner portions of the male die at the opposite sides of the opening therethrough terminating a distance from the cross member connecting the 65 said opposite sides, the outer portions of said opposite sides continuing and having connection with the said cross member, and a forming die adapted to operate through the said openings and co-acting with portions of the curvilinear side of the opening 70 through the male die to form portions of the flanges at the opposite edges of said plate and also with the remaining portion of said curvilinear side to form a flange 75 upon said plate intermediate said edge flanges, which intermediate flange extends in a direction opposite that in which the said edge flanges extend.

10. In combination, male and female dies 80 having openings extending therethrough, the inner portion of the male die at the opposite sides of the opening therethrough terminating at points in front of the rear ends of the outer portions of the said sides, 85 and the said outer portions continuing and projecting laterally to form overhanging portions, and a forming die operating in said openings.

In testimony that I claim the foregoing 90 as my invention, I have hereunto signed my name this 17th day of December, A. D. 1917.

WILLIAM NEES.
